Inventor:

W. Siegfried
B. Singer Atty.

UNITED STATES PATENT OFFICE.

WILHELM SIEGFRIED, OF ERFURT, GERMANY.

PIN TICKET.

Application filed November 14, 1924, Serial No. 749,968, and in Germany April 7, 1924.

This invention relates to tickets or labels adapted to be attached to fabrics, clothing, or other merchandise of various kinds, by means of two pins rigidly secured to the 5 ticket. These two pins may be formed by two wires singly secured to the ticket, or by the ends of a bowed wire.

The essential feature of the invention consists in arranging the base-point of one of 10 said pins at such a distance from the base-point of the other pin that the pins, after having pierced the fabric or the like, can be simultaneously and completely bent down, the one towards the other, by means of finger 15 pressure acting from the outer side of said pins, and the points of said pins can be pressed down upon or into the fabric without any possibility that the fingers acting upon the pins hinder each other.

20 In comparison with the pin-tickets hitherto known which have the pins at so short a distance from each other that the pins must be bent outwardly by gripping upon the pin-points, the novel pin-ticket offers the advantage that the pins can be bent down without touching the points of said pins, and without danger of injuring the fingers of the manipulating person.

25 In order to provide for the pin-points being very closely pressed upon or into the fabric, these portions of the wire which produce the rigid association of the pins to the ticket, i. e., either the head uniting the pins and preferably bent over the edge of the 30 ticket or the winding of the wire at the base-points of the single pins, may extend into the space between the pins, such extending portions being arranged at a small distance from the pins in order to form an elevation, a rib or a wall for each of the pins 35 when the latter are bent down towards each other, whereby said pins when bending down are curved in such a manner that the pin-points enter into the fabric or the like.

40 45 This effect may be exaggerated by manufacturing the pins curved outwardly. By this means the pin-points, on bending the pins towards each other and down to the article to be marked, cannot lay themselves 50 flat on the clothing or the like, but must under all circumstances enter the fabric. Another advantage offered by this feature consists in the fact that the pin-points, after

the pins have been bent down, lie below and between the curved portions of the pins, 55 whereby a complete protection for the pin-points is effected.

The head or wire-bow uniting the pins, and arranged on the back-side of the ticket may be provided in that portion which extends into the space between the pins, with inflections within which the pins are standing, and which are so close to the pins that they act as abutment and prop for the pins on bending said pins towards each other. 60 65 By this means, among other advantages, the effect is offered that the material of the ticket is prevented from being torn in attaching the ticket to the article to be marked.

70 The head or wire-bow arranged on the back-side of the ticket may, furthermore, be provided with an upward bending, behind which the pin-points are completely protected when the pins are bent towards each other and down upon the fabric.

75 In order to cause the pin-points to enter into the fabric at a still greater extent, the ticket may be provided with an excavation stamped at that place where the pin-points, after having been pressed down, will touch the ticket.

80 85 By the main feature of the invention, and by the various improvements mentioned before, a pin-ticket of cheap and simple construction is provided which may be conveniently and without any danger manipulated and quickly attached at any place of the fabric or other article to be marked; further a pin-ticket is provided, the pins of which can be simultaneously and completely 90 bent towards each other and down upon the fabric by means of two fingers acting upon the outer side of the pins, whereby the pin-points entering into the fabric are prevented from injuring as well the hands of 95 the manipulating person as the fabric, clothing, or the like.

80 100 Several different forms of pin-tickets embodying this invention and showing the main features of same are illustrated in the accompanying drawings:

105 Fig. 1 is a plan view of one form of the novel pin-ticket looking towards the back-side thereof, the pins being formed by the ends of a wire which is arranged on the back-side of the ticket;

Fig. 2 is a plan view of the form in accordance with Fig. 1 looking toward the face of the ticket;

Fig. 3 is a longitudinal section on the line 5 A—B of Fig. 1;

Fig. 4 is a cross section on the line C—D of Fig. 1 through the ticket after the pins have been bent down toward each other and upon the fabric;

10 Fig. 5 is a top view of the pin-ticket shown in Figs. 1 to 3;

Figs. 6 and 7 illustrate another modification of the novel pin-ticket having two single pins rigidly fastened on the ticket; 15 and

Figs. 8, 9 and 10 show still another modification with a head or wire-bow uniting the pins and having an upward bending on the back-side of the ticket.

20 Referring to the construction illustrated in Figs. 1 to 5, 1 designates the ticket, and 2 a head or wire-bow rigidly secured thereto, the ends of which head forming the pins 3, 3 with the pin-points 4, 4. The head 2 lies close to the back-side of the ticket and is bent over the edge 6 of same. The pins 3, 3 are passed through the ticket at such a distance from each other that they can be simultaneously bent toward each other by 25 means of two fingers acting upon the outer side of said pins 3, 3, whereby the pins are pressed down upon the fabric, clothing, or the like, 7. The head or wire-bow 2 extends into the space between the pins 3, 3 in order to form elevations, ribs or walls, over which the pins are to be bent down towards each other. These elevations effect a curving of the pins when said pins are pressed down to the fabric 7.

As is obvious from Fig. 5, the pins 3 are curved outwardly and offset from their base portions and thereby held in such position in view of the plane of the ticket that the pin-points 4, notwithstanding the curvation 30 of the pins 3, pass through the fabric 7 in straight or nearly straight direction.

The head or wire-bow 2 on the back-side of the ticket has curved portions 8 within which the pins 3 are standing, and which 35 act as abutments and props for the pins when said pins are bent towards each other.

The ticket 1 is provided with a recess 9 stamped or embossed at that place where the pin-points 4, after having been bent down, 40 will lie upon the fabric, clothing, or the like. By this means the pin-points 4 are caused to enter still deeper into the article to be marked. The head or wire-bow 2 is curved or bowed at 10 partly around said 45 recess 9, in order to give full play to the fingers for pressing down the pin-points.

Figs. 6 and 7 show a modified form of the invention having two single pins rigidly secured to the ticket, said single pins being provided at their base portions with windings 14 within which the pins 3 are held, and which serve as elevated abutments when the pins are bent down towards each other. 65

Figs. 8 to 10 illustrate another modification of the pin-ticket similar to the construction shown in Figs. 1 to 5. The arrangement in Figs. 8 to 10 differs from that illustrated in Figs. 1 to 5 mainly in the fact that the head or wire-bow 2, at that place, where the points 4 of the pins 3 bent 70 down come to lie upon the fabric, is provided with a curvation or bending 13 directed at an angle to the plane of the ticket. Thus, when the pins 3, 3 are bent down towards each other, the pin-points 4 are covered and protected by said curvation or bending 13 which is perceptible through the fabric, clothing, or other article to be marked. 80

Various changes in details may be made without departing from the scope and spirit 85 of the invention as described in the specification and set forth in the claims.

Having now particularly described and ascertained the nature of my said invention, and in what manner the same is to be performed, I declare that what I claim is:—

1. In a pin-ticket, the combination of a ticket, a pair of pins extending through the ticket and having a common connecting portion forming a base arranged on the same side of the ticket as the pins, said connecting portion having bent portions forming abutments arranged against and embracing portions of the peripheries of the pins, the length of said connecting portion being such as to space the pins apart and permit the bending thereof toward each other and across said abutments, and said connecting portion also having an intermediate curved portion which extends downwardly on the ticket below the common plane of the said pins. 90

2. In a pin-ticket, the combination of a ticket, a pair of pins extending through the ticket and having base means on the side of the ticket from which said pins project, said pins being spaced apart a distance sufficient to permit the bending of the pins toward each other and across the base means and being offset from their base means so that when so bent their points will be in close proximity to each other and will extend through a fabric to which the ticket is attached by said pins, said ticket having a recess to receive and cover the points of the pins. 100

In testimony whereof I affix my signature.
WILHELM SIEGFRIED.
